UNITED STATES PATENT OFFICE.

JOHN BROWN, OF LORAN, ILLINOIS.

HOUSE-MOVING TRUCK.

SPECIFICATION forming part of Letters Patent No. 239,599, dated April 5, 1881.

Application filed December 18, 1880. (No model.)

To all whom it may concern:

Be it known that I, JOHN BROWN, of Loran, in the county of Stephenson and State of Illinois, have invented certain new and useful Improvements in House-Moving Devices; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved house-moving device, and Fig. 2 is a vertical sectional view.

Similar letters of reference indicate corresponding parts in both figures.

This invention relates to an improved house-moving device, consisting, essentially, of a frame supported upon a set of rollers and having a bolster provided with a pointed bolt to retain the device in position when adjusted, as will be hereinafter more fully described, and particularly pointed out in the claim.

In the drawings hereto annexed, A represents a strongly-built frame, square or rectangular in shape, and provided in its sides with boxes or bearings for the journals B of a pair of rollers, C C, made of wood, about eighteen inches in diameter, the spindles or journals being about six inches.

At each end the frame A is provided with a hook, staple, or other means of attachment, D, to enable several of said frames to be conveniently coupled together by chains or rods, so as to enable the draft to be readily attached.

The frame A is provided with a bolster, E, placed transversely across its top, as shown, the sides of said bolster being beveled at F F, enabling a crowbar or other tool to be readily inserted between the bolster and the sill of the house, whenever necessary in handling the house after it has been let down upon the frame.

Centrally upon the bolster is secured a bolt, G, having a pointed head, H, which, after the house is let down upon the frame, enters the

sill and prevents accidental displacement of the frame.

The method of using my invention and its advantages will be readily understood from the foregoing description, taken in connection with the drawings hereto annexed.

Two or more of my improved roller-frames, according to the size of the house to be moved, are adjusted under the sill on each side of the house, which may then be readily moved in the usual manner. Displacement of the frames is prevented by the pointed bolt G. The friction is but slight, and the house being actually supported upon my improved trucks or roller-frames, the frequent shifting of rollers necessary when loose rollers are used is avoided. Simplicity, cheapness, and durability are other important qualities of my invention, and the ease with which it can be handled is obvious.

I am aware that trucks having spikes arranged upon their upper sides for engaging with the article mounted thereon to hold it in position during transportation of the same, also a truck for moving buildings having beveled bolsters with intermediate tilting supports, is old, and such I do not wish to be understood as claiming, broadly, as of my invention.

Having thus described my invention, I claim and desire to secure by Letters Patent of the United States—

The herein-described house-moving trucks, consisting of a frame, A, having rollers C C, transverse bolster E, having central pointed headed bolt G, and beveled sides F F, inclining from said bolts toward the ends thereof, and means whereby two or more of said trucks may be connected together, as specified.

In testimony that I claim the foregoing as my own I have hereto affixed my signature in presence of two witnesses.

JOHN BROWN.
